(57) **CLAIM**

The ornamental design for an irrigation spike as shown and described.

DESCRIPTION

FIG. 1 is a perspective view of an irrigation spike showing my new design;

FIG. 2 is a perspective view of the irrigation spike of FIG. 1;

FIG. 3 is an elevation posterior view of the irrigation spike of FIG. 1;

FIG. 4 is an elevation anterior view of the irrigation spike of FIG. 1;

FIG. 5 is a first side elevation view of the irrigation spike of FIG. 1;

FIG. 6 is a second side elevation view of the irrigation spike of FIG. 1;

FIG. 7 is a bottom plan view of the irrigation spike of FIG. 1; and,

FIG. 8 is a top plan view of the irrigation spike of FIG. 1. The broken lines shown in FIGS. 1-8 are for the purpose of illustrating portions of the irrigation spike that form no part of the claimed design.
